BOOK HOLDER

Louis Hernandez Campos, New York, N. Y.

Application May 28, 1935, Serial No. 23,935

1 Claim. (Cl. 45—80)

This invention relates to the class of holders and easels for holding books, magazines and the like, in open condition for reading, and also for displaying various commercial articles, advertising cards, pictures and the like.

The principal object of the invention is the provision of improvements in a device of the indicated character whereby the device may be readily used for the intended purposes, whereby 10 the device may be folded compactly to occupy a small space when not in use, and so that it may be enclosed in a flat box or the like for convenience in handling by merchants and for making deliveries and shipments of the devices, and 15 whereby the device will be of efficient and substantial design.

The nature of the invention and its distinguishing features and advantages will appear when the following specification is read in connection 20 with the accompanying drawing in which—

Figure 1 is a perspective view of a device embodying the invention set up for use;

Figure 2 is an enlarged section taken approximately on the line 2—2 of Figure 1;

Figure 3 is a section of the device folded; and

Figure 4 is a view looking down on the device set up for use.

Referring now more particularly to the several views of the drawing, it will be apparent that the 30 device of the present invention embraces an easel consisting of a frame 10 of inverted U-shape, the side portions 11 being connected by a cross-piece 12. The opposite ends 13 of the cross-piece 12 are bent at a right angle and are 35 secured to the portions 11, respectively, in any suitable manner. In the present instance, the ends 13 are riveted to the portions 11, as at 14. A cross-piece 15 is pivotally connected with the lower ends of the portions 11. The cross-piece 15 40 is L-shaped in cross section to provide a support or rest 16 and a notched flange 17 integral therewith. The cross-piece is pivotally connected with the lower ends of the portions 11, and in the present instance, by lugs 18 on the opposite ends of 45 the flange 17 and extending rearwardly at right angles with respect thereto, and to pivots 19 which extend through the lugs 18, respectively, and into the portions 11. The extremities of the rest 16 engage the portions 11, as at 20 thus limiting the movement of the cross-piece 15 in one direction so that the rest 16 will be disposed approximately at a right angle to the frame 10. The frame 10 has connected therewith a suitable brace or prop 21. In the present instance, the 50 prop 21 is substantially of V-shape, and is con-

nected with the portions 11 by pivots 22 in axial alignment with each other. The prop 21 has a notch 23.

The device also includes a rectangular frame 24 constituting a base for the easel. The frame 24 is pivotally connected with the lower ends of the portions 11 of the frame 10 by pivots 25. A rack consisting of a notched member 26 is secured within the frame 24. This is accomplished by riveting the opposite ends of the rack to the front and rear portions of the frame 24, as at 27. The rack 26 is designed and adapted to cooperate with the prop 21 to retain the easel 10 in different angular positions in relation to the base frame 24. In this connection, it is to be observed that the 15 notch 23 in the prop 21 engages the rack.

In accordance with another feature of the invention, the device is provided with holders in the form of bowed springs at 28, connected with the rest 16, so as to engage the leaves of a book, 20 or any other article placed on the rest and leaning against the easel frame 10, to prevent displacement thereof. A connection is provided between the rest 16 and one end of each of the springs 28. The said connection includes a flat 25 part 29 having an opening 30 therein to receive a strap eye 31 which is secured to the rest 16 between its ends. The inner end of each spring 28 is pivotally connected with the part 29, as at 32 for adjustment with respect to the part 29. The 30 springs 28 are thus connected for pivotal movement with respect to the part 29, and the part 29 is connected for pivotal movement with respect to the rest 16. The part 29 may be moved into engagement with the edge of the rest 16 disposed at 35 a right angle with respect thereto, thereby limiting its movement in one direction, and in this position of the part 29, the springs 28 may be swung so that their free ends will be disposed above the rest 16 to engage the leaves of a book 40 or any other object placed on the rest 16 leaning against the easel frame 10, as shown in Figure 2.

The member 29 together with the springs 28 may be swung over the upper surface of the rest 16, the cross-piece 15 may be swung over the 45 frame 10, the prop 21 may be swung to a position within the frame 10, and the frame 10 may be swung to a position within the base frame 24, the latter being large enough to accommodate the frame 10. In this manner, the components of the 50 device may be folded compactly, as shown in Figure 3, to occupy a relatively small space when not in use, and to be enclosed within a flat box or the like for easy handling by merchants and also for delivering and shipping quantities of the devices. 55

It will also be obvious that the components of the device may be set up to enable the use of the device for the purposes mentioned.

I claim:

- 5 A book holder comprising a substantially U-shaped base, a substantially U-shaped frame, means for pivotally connecting the open ends of said base and said frame together, an adjustable prop for holding said frame in different positions in respect to said base, a rest L-shaped in cross section positioned so that one leg of the rest acts as an article support and the other leg

acts as a retaining flange, said retaining flange being provided at each end with an inturned ear and said support being formed at its ends with extensions overlapping the arms of said U-shaped frame whereby the swinging movement of the rest in one direction is limited, a pivot member for each of said ears for pivotally connecting the ears to the respective arms of said frame, and resilient means carried by said support centrally thereof for holding an article on the support against displacement. 5 10
